To all whom it may concern:

Be it known that I, John Tuman, a citizen of the United States of America, residing in the city of New York, county of New York, and State of New York, have invented a new, original, and ornamental Design for a Dress, of which the following is a specification, reference being had to the accompanying drawing, forming part thereof.

Fig. 2 is a rear view thereof.

Fig. 3 is an enlarged view of one of the sleeve portions of the dress.

Fig. 4 is an enlarged fragmentary view of the collar portion of the dress showing the embroidery.

The characteristic feature of my design resides in the specific embroidery on the sleeve and collar portions of the specific dress as shown.

I claim:

The ornamental design for a dress, substantially as shown and described.
